UNITED STATES PATENT OFFICE.

JULIUS A. C. FICHTMUELLER, OF STAPLETON, NEW YORK, ASSIGNOR TO DIAMOND DECORATIVE LEAF COMPANY, OF STAPLETON, NEW YORK, A CORPORATION OF NEW YORK.

PROCESS OF MAKING DECORATIVE METALLIC LEAF.

Application filed March 28, 1921. Serial No. 456,419.

To all whom it may concern:

Be it known that I, JULIUS A. C. FICHTMUELLER, a citizen of the United States, and resident of Stapleton, in the borough of Richmond, county of Richmond, city and State of New York, have made a certain new and useful Invention Relating to Processes of Making Decorative Metallic Leaf, of which the following is a specification, taken 10 in connection with the accompanying drawing, which forms part of the same.

This invention relates to processes of making decorative metallic leaf of the type referred to in my former Patents, No. 976,994 of November 29, 1910 and No. 1,160,979 of November 16, 1915, by which the leaf after being sprayed or otherwise applied to the paper or other backing material is loosened or more or less freed from the backing as by 20 passing the leaf and backing through an aqueous solvent when a water soluble material is used between the leaf and backing paper itself. Then the leaf and backing may be wound or rolled up into a roll which 25 allows still further time for the solvent to effect its loosening or dissolving action on the sizing then the end of the paper backing may be separated from the cooperating surface of the leaf and unwound for one or 30 more convolutions, so that the previously exposed surface of the leaf is brought into contact with the unsized or plain back of the backing paper. Rolling the material effects sufficient adhesion between these 35 contacting surfaces, so that the leaf may be unrolled or withdrawn from the roll in a substantially continuous manner, so that the previously connected and more or less sized surfaces of the backing and leaf are thus 40 exposed on the outside of the compound strip or web. By passing this unwound web or strip through water or other solvent material, the size or adhesive may be dissolved or removed from these exposed surfaces of 45 the strip or web to the desired extent after which the web may be rewound, preferably in connection with a sheet of absorbent or blotting paper which facilitates the drying of the material, and also prevents sticking of 50 the continuous strip of leaf and backing. Thereafter the continuous strip or web of decorative leaf may be unwound from this roll and wound up with a strip or

sheet of tissue or other paper or in connection with the backing paper itself in some cases, so that rolls of this decorative leaf suitable for stamping and other purposes may be readily made up for sale, in which the decorative leaf is substantially continuous and uniform in character and without objectionable doubled or patching portions which is of decided advantage for many purposes. The continuous and substantially uniform character of the decorative leaf of 55 any desired color and material may be advantageously secured by forming the leaf on the backing by a spraying process as referred to in my former patents, or if desired other forms of application of the liquid material may be used as therein referred to. Also while the water soluble side or face of the backing paper on which the leaf is sprayed or formed is desirable for many purposes, yet other forms of smooth or sized 60 surfaces may be used for this backing material and wax or other substantially smooth or other impervious coatings may in some cases be employed, the leaf being removed from the backing after formation thereon 65 by the use of suitable solvent or heat treatment or both as is referred to in my former 70 patents in greater or less detail.

In the accompanying drawing showing in a somewhat diagrammatic way illustrative apparatus for this purpose,

Fig. 1 is a longitudinal section through a diagrammatic spraying or coating machine.

Fig. 2 is a similar diagrammatic view through the apparatus which may be used 90 for loosening and rerolling the leaf and backing; and

Fig. 3 is a top view thereof.

Figs. 4 to 6 are diagrammatic views of 95 these processes; and

Fig. 7 is a perspective view of a roll of the completed leaf.

As is indicated in Fig. 1 the metallic or other decorative leaf may be continuously formed by a spraying process in the manner 100 described in detail in my prior patents, by forming the leaf on a continuous strip of backing paper which may be drawn as needed from the supply roll A². This strip of paper may be carried beneath the guide 105 rolls m, arranged above the table or support M, so that this backing paper is held in substantial contact with the table and can be

fairly taut as it is fed over the same. As this backing passes through or under the spraying hood or chamber M^1 the leaf material may be sprayed or applied to the upper sized surface of this backing paper by manually directed or other spraying apparatus, so as to form the leaf a^1 on this backing. The leaf dries or hardens as the backing travels over the table M which has sufficient length so that the leaf and backing may be wound into a roll A at the end of this table for instance.

As is indicated diagrammatically in Fig. 2 the roll A of adhesively secured or connected leaf and backing paper may be continuously unrolled and the compound strip passed through the water or other solvent in the tank B as the strip passes beneath the one or more guide rolls b . In this way the solvent sufficiently dissolves, softens or loosens the water soluble or other size which holds the leaf upon the backing, so that these two strips are largely or fully loosened by the time they are rewound in moist condition for instance into the roll C . This roll C is then preferably unwound in reverse position as can be clearly seen by reference to Figs. 4 to 6 where the composite strip is indicated as comprising the backing a and the leaf a^1 . The end of the backing a may be unwound as indicated in Fig. 5 and simultaneously separated from the adjacent surface of the leaf to which it has been previously connected. Then when the backing has been unwound from the roll for a complete convolution the end of the leaf a^1 comes in contact with the plain or reverse side of this backing a as shown in Fig. 6, so that the two may thus be unwound together from the roll C and adhere sufficiently to make possible the subsequent treatment of the leaf and backing. As indicated in Fig. 2 the roll C may be mounted above the tank D when this unrolling takes place and the unrolled strip of leaf and backing may be carried down through the water or other solvent in the tank, the strip passing if desired beneath the guide roll d near the bottom of the tank. In this way the partly dissolved or loosening sizing material which is now on the exposed or outer surfaces of this compound strip may be washed off or removed by the liquid in the tank in connection if desired with various agitating or washing devices such as the brushes or paddles J which may be formed with rubber or other ribs or projections and rotated in the tank adjacent to or in contact with the exposed surface of the backing strip, so as to remove or wash the sizing material therefrom. If desired also a water inlet device H may be used preferably at about the point where the backing leaves this tank and may comprise a plate h , substantially in contact with the

backing along which jets of water or other solvent liquid may be directed from the inlet pipe H^1 . Thus this solvent liquid may be continuously supplied to the tank and continually or otherwise removed therefrom by any suitable means as by the water outlet I , which may have a guide plate i adjacent the upper surface of the liquid to receive this solvent liquid which may be thrown up by the brush or paddle J for instance. In some cases one or more brushes or agitating paddles between the descending and ascending web of material may be arranged to cooperate with the leaf a^1 and are preferably slowly rotated out of contact therewith to agitate the water or other solvent and promote its action on the leaf so as to remove the size therefrom.

In some cases it is desirable to remove surplus water etc. from the compound strip after it comes out of this tank D and for this purpose the strip may be carried over the roll f and beneath the cooperating wiper or doctor device F which may have a yielding rubber end or face to suitably engage the leaf. The leaf and backing may then be wound up on the spool or roll E together with a strip or web of any suitable absorbent or blotting paper or other material, which may be withdrawn from the roll G and of course these rolls or any of them may be rotated by hand through suitable cranks as indicated in Fig. 3 or by suitable belts or other power operating connections as is well known in this art. In some cases however, especially where the size has been substantially completely removed from the backing and leaf, they may be more or less dried by removing the liquid therefrom and allowing them to dry by carrying the strip through the air or drying chambers for a sufficient distance before winding the same into roll form in which the leaf may be shipped, sold and used if desired. Of course the substantially continuous strip or web of leaf may be cut or slit to any desired width at any suitable stage of the process and if desired the roll E may be rewound so that the continuous strip of leaf a^1 may be wound up with tissue paper or other desired material a^2 so as to form the commercial roll shown in Fig. 7. These commercial or service rolls of leaf and tissue paper etc., may comprise strips of leaf of a number of hundred of feet in length which may be formed in this way of substantially uniform character so as to be free from objectional doubled or patching portions and are therefore decidedly advantageous for many purposes.

This invention has been described in connection with a number of illustrative methods, steps, materials, conditions, apparatus, devices and orders of steps to the details of which disclosure the invention is not of

course to be limited since what is claimed as new and what is desired to be secured by Letters Patent is set forth in the appended claims:

5. 1. The process of removing sprayed decorative leaf from adherent paper backing sized with soluble material on which the leaf has been formed, which comprises passing the backing with the adherent leaf 10 thereon through aqueous solvent material to loosen, soften or dissolve the soluble sizing material on the backing, winding the leaf and backing into a roll and thereby causing the previously exposed surface of the leaf to 15 slightly adhere to the unsized reverse side of the paper backing in the adjacent convolution, unrolling the backing from the roll to separate the adhesive sized face of the backing from the surface of the leaf to which it has 20 been secured and expose the previously adhesively connected surfaces of the leaf and backing while the opposite surfaces of the backing and leaf are in substantial engagement, passing the unwound backing and leaf 25 through aqueous solvent material to remove soluble adhesive from the exposed surfaces of the backing and leaf, removing moisture from the leaf and winding the leaf into a roll with a continuous sheet of interposed 30 absorbent paper.
2. The process of removing sprayed decorative leaf from adherent paper backing sized with material on which the leaf has been formed, which comprises passing the 35 backing with the adherent leaf thereon through material to loosen, soften or dissolve the sizing material on the backing, winding the leaf and backing into a roll and thereby causing the previously exposed surface of 40 the leaf to slightly adhere to the unsized reverse side of the paper backing in the adjacent convolution, unrolling the backing from the roll to separate the adhesive sized face of the backing from the surface of the leaf to which it has been secured and expose the 45 previously adhesively connected surfaces of the leaf and backing while the opposite surfaces of the backing and leaf are in substantial engagement, passing the backing and leaf 50 through solvent material to remove soluble adhesive from the exposed surfaces of the backing and leaf and winding the same into a roll.
3. The process of removing decorative 55 leaf from adhesively connected paper backing sized with soluble material on which the leaf has been formed, which comprises treating the backing with aqueous solvent material to loosen, soften or dissolve the soluble 60 sizing material on the backing, winding the leaf and backing into a roll and thereby causing the previously exposed surface of the leaf to slightly adhere to the unsized reverse side of the paper backing in the adjacent 65 convolution and unrolling the backing
- from the roll to separate the adhesive sized face of the backing from the surface of the leaf to which it has been secured and expose the previously adhesively connected surfaces of the leaf and backing while the opposite 70 surfaces of the backing and leaf are in substantial supporting engagement.
4. The process of removing decorative leaf from adhesively connected paper backing sized with material on which the leaf has 75 been formed, which comprises treating the backing to loosen the sizing material on the backing, winding the leaf and backing into a roll and thereby causing the previously exposed surface of the leaf to slightly adhere 80 to the unsized reverse side of the paper backing in the adjacent convolution and unrolling the backing from the roll to separate the adhesive sized face of the backing from the surface of the leaf to which it has been 85 secured while the opposite surfaces of the backing and leaf are in substantial supporting engagement.
5. The process of removing decorative leaf from adhesively connected paper backing on 90 which the leaf has been formed, which comprises treating the backing with the adherent leaf thereon with solvent to loosen or soften the adhesive material on the backing, winding the leaf and backing into a roll and 95 thereby causing the previously exposed surface of the leaf to slightly adhere to the reverse side of the paper backing in the adjacent convolution, unrolling the backing from the roll to separate the adhesive face 100 of the backing from the surface of the leaf to which it has been secured and expose the previously adhesively connected surfaces of the leaf and backing while the opposite surfaces of the backing and leaf are in substantial 105 engagement, passing the unwound backing and leaf through solvent material to remove soluble adhesive from the exposed surfaces of the backing and leaf and winding the leaf into a roll with a continuous sheet 110 of interposed absorbent paper.
6. The process of removing decorative leaf from adhesively connected paper backing on which the leaf has been formed, which comprises treating the backing with the adherent leaf thereon to loosen or soften the adhesive material on the backing, winding the leaf and backing into a roll and thereby causing the previously exposed surface of the leaf to slightly adhere to the reverse side 115 of the paper backing in the adjacent convolution, unrolling the backing from the roll to separate the adhesive face of the backing from the surface of the leaf to which it has been secured while the opposite surfaces of the backing and leaf are in substantial 120 engagement, and winding the leaf into a roll with a continuous sheet of interposed absorbent paper.
7. The process of removing a substantially 125

- continuous strip of sprayed decorative leaf from adhesively connected backing on which the leaf has been formed, which comprises reducing the adherence between the backing 5 and the adherent leaf thereon, winding the leaf and backing into a roll and thereby causing the previously exposed surface of the leaf to slightly adhere to an adjacent paper supporting strip and unrolling the 10 backing from the roll to separate the leaf from the backing while the opposite surface of the leaf and supporting strip are in substantial engagement.
8. The process of removing sprayed decorative leaf from the sized paper backing on which it is formed, which comprises moistening and softening or loosening the sizing material, winding the leaf and backing into a roll, and disengaging the leaf from the 15 sized surface of the backing paper on which it was formed and simultaneously unrolling the backing and leaf to bring the leaf into engagement with the opposite surface of the backing and removing sizing from 20 their exposed outer surfaces.
9. The process of removing decorative leaf from the sized paper backing on which it is formed, which comprises softening or loosening the sizing material, winding the 25 leaf and backing into a roll, and disengaging the leaf from the sized surface of the backing paper on which it was formed and simultaneously unrolling the backing and leaf to bring the leaf into engagement with the opposite surface of the backing.
10. The process of removing decorative leaf from the coated surface of backing paper on which it is formed, which comprises loosening or dissolving the coating on said 30 backing paper to facilitate the removal of the leaf therefrom and continuously removing said leaf from the coated surface of a roll of said backing paper and simultaneously bringing it into contact with a relatively non-adherent paper surface as the leaf and backing paper are being unrolled.
11. The process of removing decorative leaf from the coated surface of backing paper on which it is formed, which comprises loosening or dissolving the coating on said 35 backing paper to facilitate the removal of the leaf therefrom and continuously removing said leaf from the coated surface of a roll of said backing paper and simultaneously bringing it into contact with a relatively non-adherent paper surface as the leaf and backing paper are being unrolled.
12. The process of removing sprayed decorative leaf from the coated surface of backing paper on which it is formed, which comprises loosening or dissolving the coating on said 40 backing paper to facilitate the removal of the leaf therefrom and continuously removing said leaf from the coated surface of a roll of said backing paper and simultaneously bringing it into contact with a relatively non-adherent paper surface as the leaf and backing paper are being unrolled.
13. The process of removing decorative leaf from the coated surface of backing paper on which it is formed, which comprises loosening or dissolving the coating on said 45 backing paper to facilitate the removal of the leaf therefrom and removing said leaf from the coated surface of a roll of said backing paper and simultaneously bringing it into contact with a relatively non-adherent paper surface.
14. The process of removing decorative leaf from the surface of backing paper on which it is formed which comprises loosening the leaf on said backing paper therefrom and continuously removing said leaf from 50 said surface of a roll of said backing paper and simultaneously bringing it into supporting engagement with another paper surface.
15. The process of removing decorative leaf from the surface of backing on which it is formed, which comprises loosening the leaf on said backing therefrom and removing said leaf from said surface of said backing and simultaneously bringing it into supporting engagement with another paper surface.

JULIUS A. C. FICHTMUELLER.
